PLAY GARMENT

Henry Louis Martiny, New Orleans, La.

Application August 5, 1939, Serial No. 288,653

3 Claims. (Cl. 2—79)

My invention relates to improvements in play garments, and particularly to means incorporated therein in cooperative relation whereby maximum freedom of motion of the wearer is provided for at the points of greatest activity, such as the shoulders, the waist, the crotch, and the legs, and an important object of the invention is to provide arrangements of this character which enable the production of a garment of the character indicated which is practical, relatively inexpensive, and is suitable alike for grown-ups and children, for sports, for work and for lounging.

Other important objects and advantages of my invention will be apparent from a reading of the following description taken in connection with the drawings, wherein for purposes of illustration I have shown preferred embodiments of my invention.

In the drawings:

Figure 1 is a general front elevational view showing a coverall type of play suit illustrating the invention.

Figure 2 is a fragmentary side elevational view showing a modified form of trouser legs.

view taken through Figure 1 approximately on the line 3—3 and looking downwardly in the direction of the arrows.

Figure 5 is a fragmentary top plan view showing the flexible and expandable crotch construction.

Figure 6 is a fragmentary front elevational view similar to Figure 1 but showing the front of the garment open.

the line 1—1 and looking toward the right in the direction of the arrows.

arrows. Referring in detail to the drawings, the numeral 5 generally designates the garment which for illustrative purposes may consist of a blouse section 6 and a trouser section 7, although the invention is not necessarily limited to a combination of such sections, it being entirely feasible to provide separate shirt and separate trousers to be worn without relation to each other or to be separably connected, whereas the present

waist and trousers are shown as connected in a coverall form of garment. With respect to the blouse or shirt section 6, the same may preferably be of a loose fitting type provided with a suitable collar 8 at the neck opening which is V-shaped as indicated by the numeral 9 and has cords 10 fastened to one side of the opening with snap fasteners or the like 11 on the opposite side of the opening for securing the free ends of the cords. From the lower end of the neck opening 9 to the belt area 12 the front of the waist 6 is opened and provided with a slide fastener closure 13 which extends either as far as the belt area or all of the way down below the belt area to close also the crotch opening 13'. The sleeves 14 and 15 may be of long or short type but in either case are connected to the armhole portions 16, 17 of the waist 6 by means of "lastex" connectors or inserts 18, 19, respectively, which are wider at their middle as indicated by the respective numerals 20 and 21. Suitable breast pockets 22 and 23, respectively, may be provided on the breast portion of the front of the waist or shirt section 6.

The trouser or pants section 7 is composed of the legs 24, 25, respectively, which depend from and form a part of the body portion 26 which is provided at the back with a back seam to provide for adequate alterations. The front of the body portion 26 is closed except for the crotch opening 13' already mentioned which may be terminated at the waist area or be a part of or a continuation of the shirt opening, as indicated in Figure 6 of the drawings. The slide fastener 13 may be extended to operate also along the one side of the crotch opening or a separate slide fastener (which is not shown) may be utilized for closing the crotch opening 13'. A covering strip 27 extends along the front opening of the shirt section and along the crotch opening 13' to cover up the slide fastener when the garment is closed.

The legs of the garment may be short-length, knee length like knickerbockers, three-quarter length or full length and may have at the lower end thereof a tapering conical "lastex" leg gripping portion 28 which terminates at its lower end in a cuff or similar band 29 which is open at two sides and there provided with snap fasteners or buttons as indicated by the numerals 30 and 31, respectively, so that the band may be contracted on the leg of the wearer while the upper "lastex" leg portion 28 provides the desirable "give" between the band 29 and the cloth portion of the legs. If desired the legs

may be of the cuff bottom type as illustrated in Figure 6 of the drawings and be devoid of the "lastex" bottom above described, such embodiment of the invention being designated 24a and the cuff thereof 28a.

In the embodiment of the invention illustrated the waist or shirt section 6 is connected to the pants or trouser section 7 by means of a "lastex" waistband 32 which forms the connection between the said sections, thereby acting as compensator to equalize the distribution of the shirt section and the trouser section with respect to the body of the wearer during strenuous activities. At opposite front side portions the waistband 32 may be provided with pairs of openings 33, 33 and 34, 34, respectively, with the back of the waistband being provided with two relatively greatly separated belt receiving openings 35 and 36, respectively. A waist belt 37 preferably of material similar to or the same as that from which the remainder of the garment is made is guided inwardly and rearwardly through the front and rear openings 33, 33, respectively, forwardly through the rear opening 35, rearwardly through the rear opening 36 around the outside of the belt section 32 and then laterally inwardly through the first of the openings 34 and forwardly through the succeeding one of the openings 34, so that the opposite ends 38 and 39 of the waist belt are located at the sides of the front of the flexible and expansible waistband 32 as particularly well illustrated in Figure 3 of the drawings, the belt end 39 being provided with suitable rings 40 for enabling adjustably fastening the belt 37 across the front of the garment.

As illustrated particularly well in Figure 5 of the drawings the crotch portion 21 of the garment which includes the front sections 42 and 43 and the rear sections 44 and 45 is characterized by a diamond-shaped "lastex" insert 46 which displaces a corresponding amount of the cloth forming the various sections named with the corners thereof located in alignment with the respective side seams 47, 48, the rear seam 49 and the front seam 50 which is aligned with the crotch flap 51 which is disposed at the crotch opening 13'.

Attached to and forming a part of the flexible and expansible waistband 32 is the supporter which is generally designated 52 and which is made of "lastex" in the form illustrated in Figure 3 of the drawings. The portion 53 which passes between the legs of the wearer tapers to a greater width at the front end and thereat merges into two relatively wide outwardly half-elliptical parts 54 and 55 which are separated by a slot 56 and at their upper ends are sewed or otherwise suitably secured to the inner side of the waistband 32 at opposite sides of the front opening as indicated by the numeral 56 in Figure 4 of the drawings. The narrower rear end of the supporter

part 53 terminates in two relatively narrow straps 58 and 59 which are attached at relatively widely spaced points at the inner side of the back of the waistband 32 as indicated by the numeral 60 in Figure 4. The flexible and stretchable character of the support 52 and the waistband 32 cooperate to relieve the wearer of any sense of binding or tension, such as exists where the supporter is attached to ordinary cloth parts of the

garment as in the prior art.

The supporter 52 serves a dual purpose as will be understood when it is considered that upon closing the front of the garment the parts 54 and 55 come together and constitute an abdominal support which is contracted inwardly and downwardly by the downward stress placed on the lower part of the supporter, thereby affording a type of support desired by golfers, tennis players, and other persons.

20 Although I have shown and described herein a preferred embodiment of my invention, it is to be definitely understood that I do not desire to limit the application of the invention thereto except as required by the scope of the subjoined claims.

25 Having described the invention, what is claimed as new is:

1. In a garment of the type described, a shirt section and a trousers section, an elastic waistband connecting the upper end of said trousers section to the lower end of said shirt section, an elastic supporter within said trousers section comprising front portions attached to depend from the forepart of said waistband and rear portions attached to depend from the rear part of said waistband.

2. In a garment of the type described, a shirt section and a trousers section, an elastic waistband connecting the upper end of said trousers section to the lower end of said shirt section, 30 said waistband being formed with at least two belt passing openings at opposite sides of the forepart thereof and at least two belt passing openings at the back thereof, and a waist belt passing through said openings and lying along the inner and outer sides of said waistband.

45 3. In a garment of the type described, a shirt section and a trousers section, an elastic waistband connecting the upper end of said trousers section to the lower end of said shirt section, 40 said waistband being formed with at least two belt passing openings at opposite sides of the forepart thereof and at least two belt passing openings at the back thereof, and a waist belt passing freely through said openings and lying along the inner and outer sides of said waistband, the free ends of said waist belt terminating in front of the said forepart of the garment and arranged to be connected across and against the front side of the forepart of said waistband.

60 HENRY LOUIS MARTINY.
